Patented Aug. 14, 1956

178,530

TROLLING PLANER

Joseph J. Magill, Brielle, N. J., assignor to Art Wire and
Stamping Company, Newark, N. J., a corporation of
New Jersey

Application October 28, 1955, Serial No. 38,616

Term of patent 14 years

(Cl. D31—4)

Fig. 1 is a view in perspective showing a trolling planer incorporating the design of this invention;

Fig. 2 a bottom plan view;

Fig. 3 a side elevational view;

Fig. 4 a rear elevational view;

Fig. 5 a front elevational view; and

Fig. 6 a top plan view.

I claim:

The ornamental design for a trolling planer, as shown.
